US0D1006530S

(12) **United States Design Patent** (10) **Patent No.:** **US D1,006,530 S**
(45) **Date of Patent:** **** Dec. 5, 2023**

(54) **COFFEE GRINDER**

(71) Applicant: **SHENZHEN DENORGIN TECH. CO., LTD.**, Shenzhen (CN)

(72) Inventor: **Rongqiang Shi**, Shenzhen (CN)

(**) Term: **15 Years**

(21) Appl. No.: **29/810,960**

(22) Filed: **Oct. 11, 2021**

(51) **LOC (14) Cl. 31-00**

(52) **U.S. Cl.**

(57) **CLAIM**

The ornamental design for a coffee grinder, as shown and described.

DESCRIPTION

FIG. 1 is a perspective view of a coffee grinder showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an enlarged view of portion 9 shown in FIG. 1. The dash-dash broken lines in the drawings depict portions of the coffee grinder that form no part of the claimed design. The dot-dash broken lines represent boundaries of the enlarged portion and form no part of the claimed design.

1 Claim, 9 Drawing Sheets
